UNITED STATES PATENT OFFICE.

JAMES A. CRISWELL, OF MIFFLINTOWN, PENNSYLVANIA.

IMPROVEMENT IN LEGISLATIVE VOTING APPARATUS.

Specification forming part of Letters Patent No. **142,002**, dated August 19, 1873; application filed December 28, 1872.

To all whom it may concern:

Be it known that I, JAMES A. CRISWELL, of Mifflintown, in the county of Juniata and State of Pennsylvania, have invented a new and valuable Improvement in Voting, &c., Machines; and I do hereby declare that the following is a full, clear, and exact description of the construction and operation of the same, reference being had to the annexed drawings making a part of this specification, and to the letters and figures of reference marked thereon.

Figure 1 of the drawings is a representation of my machine for voting in position. Fig. 2 is a side view of same. Fig. 3 is a vertical transverse section of my voting-machine. Figs. 4, 5, 6, 7, 8, 9, 10, and 11 are details of same.

This invention has relation to a legislative vote-register, the action of which depends upon the use, as voting mediums, of white and black balls, the former color, for instance, representing "aye," and the latter "nay;" and consists in the construction and arrangement of devices whereby the "aye" and "nay" votes and the total are severally indicated upon separate dials, the mechanism appertaining directly to which is operated by the weight of the balls, the same being transferred, by suitable tubes, from the members' desks to receptacles suspended from said mechanism. The novelty consists in the construction and arrangement of devices whereby the balls, after being weighed and the desired result obtained, are transferred from their weighing-receptacles, located below the assembly-room, to the keeping and control of the assembly-clerk present in the assembly-room, to be redistributed among the members. The novelty also consists in the construction and arrangement of the parts of the clerk's distributing-desks essential to the proper distribution of the balls, and of the parts of the members' desks provided for the casting of the votes.

The apparatus which constitutes the present invention depends for its operation and utility upon the use by voters of balls of any suitable material possessing readily calculable weight. The balls are all of equal weight. Some of the balls are white and others black, the white

representing "aye," and the black, "nay." Each member is furnished with a requisite number of balls, to contain which his desk is provided with a drawer. The distribution of the balls takes place at the clerk's desk, the latter being provided with a number of drawers, A, which respectively correspond to a member's desk, each drawer being numbered according to its destination. The clerk having in charge the white and black balls distributes them in equal proportions to the drawers A, through the tubes B, which extend from the top of the clerk's desk to the several drawers, in the manner clearly shown in Fig. 11 of the drawing. After being supplied, the drawers A are transferred to the members' desks and substituted for the empty drawers thereof, which are made to take the places in the clerk's desk of the drawers for which they have been exchanged. The portion of the clerk's desk facing the clerk is provided with other drawers, to suit the requirements of that officer.

The clerk's desk may be located in any convenient part of the assembly-hall. The most appropriate position, however, is as close as possible to the elevator D, so that he may control the latter.

In Fig. 1 of the drawings, which is a plan view of an assembly-hall, E designates the clerk's desk, and F that of the chairman or presiding officer. G G¹ G² designate the registering-instruments, of which the first is used to indicate the number of "aye" votes, the second the number of "nay" votes, and the third the total of votes cast during a single ballot. Each of these registering-instruments is provided with one or more graduated dials, H, upon which the condition of the ballot is indicated by means of a revolving hand or pointer, h. The registering-instruments are similar to the ordinary spring-dial balances of commerce. To the depending beam of the register G² are attached the laterally-extending arms h', which support at their extremities the registers G G¹, or are connected to the vertically-moving beams of the latter. The registers G G¹ support, as shown, the boxes I I¹, which receive the votes or balls as they pass from the voters' desks through the inclined tubes I². The number of balls deposited is determined by their

weight, which so controls the registers as to cause them to indicate the number of votes cast. The collective weight of the white and black balls is brought to bear on the register G^2 , through the medium of the arms h' , causing said register to indicate the total vote cast. A beam, z , of the form of an inverted T, suspends each of the boxes $I I'$ from its respective register. The horizontal feet of these beams are pivoted to ears at the sides of the boxes, allowing the latter to be tilted toward an inclined way, K , which leads to the base of the elevator. After each ballot the balls are dumped from the boxes $I I'$, upon the way K , which has a channel in one side to receive and conduct the balls to an opening, k , in the side of the elevator. The elevator is designed for the purpose of transferring the balls from the inclined way to the assembly-room. This apparatus consists of an upright rectangular tube or casting, containing a carrier, k^1 , of a three-quarter cylindrical form, its mouth facing the opening k . A bail, k^2 , hinged to the sides of said carrier, has attached to it a rope, k^3 , which passes upward and over a windlass-shaft, k^4 , located at the top of the elevator. By means of said windlass and rope the carrier is raised and lowered. Into this carrier the balls are received from the inclined way and raised to the proper height. The elevator has near its top a facial extension, L , into which slides a drawer, L^1 , corresponding to one or more drawers in the clerk's desk, and interchangeable therewith. From the sides of the carrier project the centrally-located studs or arms L^2 , which hold the bail k^2 , and travel through the slots L^3 cut in the sides of the elevator. The upper parts of these slots terminate in quarter-circles, which, as the studs L^2 pass through, tilt the carrier forward and over the drawer L^1 , causing it to deposit its contents therein. Pivoted to the sides of the elevator, at the points from which the quarter-circle curves are described, are the arms M , notched in their under sides to receive the studs L^2 , when the latter reach the proper elevation. These arms move with the studs. Springs M' , suitably arranged, tend to force said arms downward; hence, when the windlass is released, they throw the carrier back to its original position, from which it has been tilted. The carrier then descends for another load, and when near the bottom of the elevator, its studs L^2 press upon the L-shaped levers L^4 , which are connected to a sliding gate, L^5 , which covers the opening. By this pressure the gate is raised, and the balls from the inclined way allowed to roll into the carrier. As soon as the latter is raised the gate falls, preventing the balls from passing into the base of the elevator. At the lower ends of the slots L^3 , India-rubber cushions N are placed, to deaden the sound of the arms or studs L^2 as the carrier falls. The elevator is under the control of the assembly-clerk.

When the drawer L^1 is filled it is transferred to the clerk's desk, and an empty drawer taken from the latter placed in the elevator. To the rear ends of the boxes $I I'$ are attached the vertical plates i , having pivoted to their upper ends the segmental bars i^1 , having the slightly curved extensions i^2 . These bars pass through slots i^3 in the beams z , and are notched at i^4 , so that when the boxes are in position the segmental bars will drop and engage with the beams z . Pins i^5 , at the upper ends of the bars i^1 , prevent the boxes from tilting rearwardly. Pivoted to lugs projecting from the plates at the rear ends of said boxes are triggers P , by raising the handles of which the extensions i^2 are acted upon, the segmental bars raised and disengaged from the beams z , and the boxes tilted. The front ends of the boxes are so inclined as to allow the balls to fall out easily when the boxes are tilted. Q designates a horizontal rotary shaft, armed with two L-shaped rods, Q' , which project, as shown, behind the boxes $I I'$, and under the triggers P . By properly turning said shaft these rods are raised so as to actuate said triggers. The shaft Q holds also two pulley-wheels, R , around which are wound cords R' , which are thence curved forward and upward and attached to sliding spring-rods S , by pulling which the shaft is turned. The spring-rods may be attached to one of the registers, or to the clerk's desk.

The drawers and various receptacles for the balls should be lined with cloth or other suitable material to deaden their sound.

The mouths of the tubes should be made flaring, so that the balls will pass out easily.

The balls v are all appropriately numbered or marked to correspond to the desks to which they respectively belong, so that the names of the voters with the character of their vote may be readily ascertained.

Each member's desk is provided with two tubes, leading from the top of the desk to the boxes $I I'$, one tube being designed for black, and the other for white balls. All the white balls pass into the box I , while all the black balls pass into the box I' . Each tube has at its upper end a cup, T , having a spring-slide, T' , at its bottom, which holds the ball during the deliberation of the voter.

What I claim as my invention, and desire to secure by Letters Patent, is—

1. The elevator D and connections, in combination with the vote-registering apparatus, substantially as specified.

2. The improved distributing-desk, having the drawers A and distributing-tubes B , substantially as and for the purpose specified.

In testimony that I claim the above I have hereunto subscribed my name in the presence of two witnesses.
